UNITED STATES PATENT OFFICE.

WILLIS P. COLEMAN, OF THE UNITED STATES ARMY.

APPARATUS FOR USE IN INSTRUCTION WITH SMALL-ARMS.

1,273,034.

Specification of Letters Patent. Patented July 16, 1918.

Application filed November 26, 1917. Serial No. 204,131.

To all whom it may concern:

Be it known that I, WILLIS P. COLEMAN, lieut. colonel, U. S. Army, a citizen of the United States, stationed at Camp Grant, 5 Rockford, in the county of Winnebago and State of Illinois, have invented certain new and useful Improvements in Apparatus for Use in Instruction with Small-Arms; and I do hereby declare the following to be a full, 10 clear, and exact description of the invention, such as will enable others skilled in the art to which it appertains to make and use the same.

My invention relates to improvements for 15 use in connection with the instruction of recruits, and even marksmen, in the proper method of holding the piece and pulling the trigger without disturbing the line of sight.

To be able to shoot a military rifle with 20 accuracy it is necessary to hold the rifle in a vise-like grip during the operation of squeezing the trigger. And to bring the recruit to a realization of the necessity for this "hold and squeeze" is the most difficult 25 part of the instruction. At present there is no satisfactory method of concentrating on this part of the instruction, although there are many devices that assist in the general instruction of rifle shooting.

30 By the hereinafter described device it will be seen that instruction is concentrated on the necessity for gripping the piece firmly and pulling the trigger without disturbing the line of sight, which makes it plainly 35 apparent to the instructor, as well as to the recruit himself, the inability of the recruit to perform this most necessary part of rifle shooting.

My invention will be more clearly understood after reference to the accompanying 40 drawings, in which:

Figure 1 is a diagrammatic view showing the apparatus used in connection with a military rifle.

45 Fig. 2 is a view on a larger scale of the stand carrying the connecting pin.

Fig. 3 shows a section along the line 3—3 of Fig. 2, and looking in the direction of the arrows.

50 Fig. 4 shows a slightly modified form of the apparatus, the view being otherwise similar to Fig. 1.

Fig. 5 is an enlarged view showing the stand carrying the electric battery, the bell 55 and needle support, the parts being shown

in section, broken along the line 5—5 of Fig. 4; and

Fig. 6 is a diagram showing the electric connections.

Referring first to Figs. 1 to 3, 1 represents 60 the rifle, 2 represents the stand having the upright stanchion 3 provided with a socket adapted to receive the metal bar 4 carrying the yoke 5, one arm 6 of said yoke carrying the contact pin 7 and the other arm 8 of said 65 yoke carrying the plate provided with a miniature target 9, which plate is connected to the arm 8 by means of the clamp screw 10.

The stand 2 and stanchion 3 are provided with insulating material and electrically 70 connected with the bar 4 secured by means of the clamp screw 11, which is connected by the conductor 12 to a source of electricity such as the battery 13, the opposite pole of the battery being connected by the conductor 14 to the band 15, which is fast on the barrel of the piece. 16 represents an electric bell or buzzer, or the like, which is operated when the electric circuit is completed. 75

In the modification shown in Figs. 4, 5 80 and 6, the stand 22 and stanchion 23 are made of wood as before, and the rod 24 is also of wood and clamped in the desired position by the clamps 23^a. This rod 24 is connected to the yoke 25, one arm 26 of which 85 carries the socket piece 26^a in which the needle 7^a is adjustably mounted as by means of the clamp screw 7^b, the other arm 28 of the yoke 25 carries the plate 28^a provided with a miniature target 9, similar to that 90 shown in Fig. 1.

The brace 29 serves not only to brace the stanchion 23 but also as a support for the bell 16. The platform 22 carries the electric cells 13 connected in series 13^a, and one terminal of the battery is connected to the conductor 12 which, after passing through the windings of the bell, is connected to the clamp screw 7^b which is in electrical connection with the adjustable needle 7^a. 100 The other terminal of the battery is connected by the conductor 14 to the conducting band 15 on the barrel of the piece as before.

The operation is the same in both forms of the device, and is as follows: 105

The recruit under instruction takes the prone position, that is flat on the ground, and adjusts the sling so as to enable him to hold the butt of the rifle close against his shoulder; he then aims at the miniature tar- 110

get 9, which is just above the conducting pin 7 or 7^a, as the case may be. When the rifle is steady the instructor moves either the pin or the stand, so that the point of the pin 5 enters slightly the mouth of the bore. The recruit is then required to pull on the trigger or "squeeze" the trigger, as it is technically termed, until the sear is released and the piece is snapped without ringing the bell. Any displacement of the muzzle of the piece will cause a contact to be made between the side of the bore and the contact pin, and the bell will ring.

By changing the height of the stand, the 15 same device may be used for the kneeling or standing position of the recruit; moreover, by varying the diameter of the pin, the degree of steadiness with which the piece must be held may be slightly varied.

20 It will be seen that with the device shown in Fig. 4, the recruit may bring the piece close to the pin, and the pin may be very readily moved longitudinally and inserted into the muzzle of the piece and then clamped 25 at the desired position.

While I have shown an electric battery as furnishing the necessary electric current, any suitable available source of electricity may be adopted. Moreover, it will be noted 30 that the same device may be used for instructing in holding and firing revolvers or pistols.

It is obvious that various modifications might be made in the herein described device, and in the construction, combination and arrangement of parts which could be used without departing from the spirit of my invention; and I do not mean to limit the invention to details except as particularly pointed out in the claims.

Having thus described my invention, what I claim and desire to secure by Letters Patent of the United States is:

1. Apparatus for use in instruction with 45 small arms comprising a frame, a metal pin of less diameter than the bore of the piece carried by said frame and adapted to be caused to project into the muzzle of the piece, a source of electricity, and an electric 50 circuit having its terminals connected respectively to the barrel of said piece, and to said pin, which circuit is closed when said pin contacts with the wall of the bore of the piece, and an electric signaling device 55 operated only when the circuit is closed, substantially as described.

2. Apparatus for use in instruction with 60 small arms comprising a frame, a metal pin of less diameter than the bore of the piece carried by said frame and adapted to be caused to project into the muzzle of the piece, a source of electricity, and an electric 65 circuit having its terminals connected re-

spectively to the barrel of said piece, and to 65 said pin, which circuit is closed when said pin contacts with the wall of the bore of the piece, and an electric bell operated only when the circuit is closed, substantially as described.

3. Apparatus for use in instruction with 70 small arms comprising a frame, a metal pin of less diameter than the bore of the piece 75 adjustably mounted in said frame and adapted to be caused to project into the muzzle of the piece, a source of electricity, and an electric circuit having its terminals connected respectively to the barrel of said piece, and to said pin, which circuit is closed when said pin contacts with the wall of the bore of the piece, and an electric signaling 80 device operated only when the circuit is closed, substantially as described.

4. Apparatus for use in instruction with 85 small arms comprising a frame, a metal pin of less diameter than the bore of the piece 90 adjustably mounted in said frame and adapted to be caused to project into the muzzle of the piece, a source of electricity, and an electric circuit having its terminals connected respectively to the barrel of said piece, and to said pin, which circuit is closed when said pin contacts with the wall of the bore of the piece, and an electric bell operated 95 only when the circuit is closed, substantially as described.

5. Apparatus for use in instruction with 100 small arms comprising a frame having a vertically adjustable yoke mounted thereon, a metal pin of less diameter than the bore of the piece adjustably mounted in said yoke and adapted to be caused to project into the muzzle of the piece, a source of electricity, and an electric circuit having its terminals connected respectively to the barrel of said piece, and to said pin, which circuit is closed 105 when said pin contacts with the wall of the bore of the piece, and an electric signaling device operated only when the circuit is closed, substantially as described.

6. Apparatus for use in instruction with 110 small arms comprising a frame having a vertically adjustable yoke mounted thereon, a metal pin of less diameter than the bore of the piece 115 adjustably mounted in said yoke and adapted to be caused to project into the muzzle of the piece, a source of electricity, and an electric circuit having its terminals connected respectively to the barrel of said piece, and to said pin, which circuit is closed when said pin contacts with the wall of the bore of the piece, and an electric bell operated only when the circuit is closed, substantially as described.

In testimony whereof, I affix my signature.

WILLIS P. COLEMAN.
